PROCESS FOR REGENERATING A SOLID
DESICCATING AGENT

William E. Perdew, Kechi Township, Sedgwick
County, Kans., assignor to Globe Oil & Refining
Company, Wichita, Kans., a corporation of
Kansas

Application January 16, 1943, Serial No. 472,574

4 Claims. (Cl. 252—274)

1

This invention relates to a process for regenerating a desiccating agent and more particularly to a process for regenerating a solid desiccating agent of the water adsorption type used for the removal of dissolved water from low boiling hydrocarbon oils.

The process of this invention is particularly useful for regenerating a desiccating agent that is used for the removal of small quantities of dissolved water from hydrocarbon oils prior to the time that the hydrocarbon oils are passed into transportation pipe lines. The small quantities of water normally found dissolved in certain hydrocarbon oils, such as gasoline, kerosene, straight-run distillate, cracked distillate, etc., may have a tendency to condense within a transportation pipe line because of the relatively low temperatures that may be encountered therein. This condensed water has a tendency to cause corrosion in pipe lines. It is well known that the dissolved water content of the hydrocarbon oil can be reduced by passing the oil over a solid adsorbent. In an oil so treated water droplets will not have a tendency to condense or precipitate in the pipe line. The rate of corrosion in the pipe line may thereby be substantially decreased or the corrosion may be entirely eliminated therein. It is an object of this invention to provide a means for reactivating, revivifying or regenerating a solid desiccating agent which may be used for reducing the dissolved water content of hydrocarbon oils prior to the time that they are passed into transportation pipe lines.

It is a further object of this invention to provide a process for regenerating the solid desiccating agent under such conditions that atmospheric oxygen or other gas is not introduced directly into the pipe line.

A further object of this invention is the provision of a process in which the solid desiccating agent is thoroughly washed during the regeneration step to remove any residues that may have been deposited therein by the passage of the hydrocarbon oil being desiccated therethrough.

A further and additional object of this invention is to provide a solid desiccating agent regeneration process wherein the agent is dried with a hot inert gas which is substantially incapable of reacting with the desiccating agent

2

or of polymerizing or forming undesirable liquid or solid products when it is contacted with a solid desiccating agent.

Further and additional objects will appear from this specification, the accompanying drawing and the appended claims.

In accordance with one embodiment of this invention, the solid desiccating agent used in the removal of dissolved water from hydrocarbon oils 10 may be regenerated by first washing the desiccating agent with a low boiling hydrocarbon liquid, passing a stream of gas into contact with the washed desiccating agent at an elevated temperature whereby to remove water therefrom in the form of a vapor, and thereafter flooding said desiccating agent with a low boiling nonaqueous liquid to prevent the contact of gases therewith prior to the time that the desiccating agent is reused for the removal of dissolved water from 20 the hydrocarbon oil being processed. If desired, the desiccating agent may be disposed in suitably enlarged chambers, and a number of these chambers may be arranged in series so that a desired degree of dissolved water removal from the oil 25 being treated may be effected. In accordance with the present invention, one of the chambers containing the desiccating agent may be cut out of the series and subjected to the regeneration process while the hydrocarbon oil being treated 30 is passed through the remainder of the chambers in series. Any low boiling hydrocarbon liquid may be used for washing the desiccating agent in the chamber prior to the actual regenerating step. A straight-run naphtha having a boiling point 35 between 300° and 400° F. may suitably be used. However, any other low boiling hydrocarbon oil may be used for the washing step, it being preferable that all the constituents thereof be evaporable so that a residue will not be left on the 40 desiccating agent during the regeneration step. The inert gas used for expelling the adsorbed water from the desiccating agent may suitably be natural gas. However, other gases, such as combustion gases, still gases, cracking gases and 45 the like, may be used. Natural gas is preferred because it is cheap and is substantially free from dust, sulfur dioxide, hydrogen sulfide, oxygen, polymerizable olefinic hydrocarbons, and other undesirable constituents. However, carbon dioxide or nitrogen or other inert gas free from

undesirable products could be used with equal efficiency. In accordance with one embodiment of this invention the hot regenerating gas, after having been contacted with the solid desiccating agent, may be cooled to condense and separate the water vapors therein and reheated and recycled to the desiccating agent in order to effect further water removal. This process therefore requires only small amounts of regenerating gas which may be continually used in the process.

For a more complete understanding of this invention, reference will now be had to the accompanying drawing wherein is shown diagrammatically an apparatus for carrying out the process of this invention. Essentially the apparatus shown in the drawing comprises three chambers 2, 4 and 6 arranged in series, each having disposed therein a solid substance, such as dried silica gel or activated alumina, capable of absorbing dissolved water from a hydrocarbon oil which may be contacted therewith. These chambers are connected in series by suitable piping, and are further arranged so that any one of the chambers may be cut from the oil treating system for purposes of regeneration while the oil to be desiccated is passed through the remaining chambers of the series.

The oil from storage containing substantial amounts of dissolved water is passed from storage through the pipe 8 to the treating chambers, and the oil from which the desired amount of dissolved water has been removed after passage through the chambers is discharged from the desiccating system to the transportation pipe line 10. Gas for the regeneration or revivification of the desiccating agent is heated in a gas heater 12, and after passage through the chamber being regenerated (2, 4 or 6) passes through the gas cooler 14 in order to condense the water vapor which separates in the water separator 16. If desired, the entire oil desiccating system can be by-passed through the pipe 18 so that the oil from storage may be passed directly to the pipe line 10 without contacting the solid desiccating agent disposed in chambers 2, 4 and 6. As shown in the drawing, a number of pipes controlled by suitable valves are provided for cutting the chambers 2, 4 and 6 into and out of the system in the manner to be described and for effecting the desired washing and treatment of the desiccating agent to effect the desired regeneration or revivification thereof.

In carrying out this process the oil to be desiccated may be passed from storage through pump 20, valve 22, pipe 8, pipe 24, valve 26, into the chamber 2. The chamber 2 has disposed therein a solid desiccating agent, preferably of the adsorption type, such as silica gel or activated alumina, for removing at least a portion of the dissolved water normally present in the oil. The oil is discharged from the upper portion of the chamber 2 through pipe 28, valve 30, pipes 32, 34 and 36, valve 38, and into the chamber 4. Within the chamber 4 is disposed another body of a solid desiccating agent which has preferably been more recently regenerated than the desiccating agent disposed within chamber 2. After contact of the oil in chamber 4 with the desiccating agent therein, the oil passes continuously from the top of the chamber 4 to the transportation pipe line 10 through pipe 40, valve 42, pipes 44 and 46, valve 48, pipe 50, pump 52, pipe 54, valve 56, pipe 58, and valve 60.

While the oil is being passed through the desiccating chambers 2 and 4 as above described,

chamber 6 has been cut out of the system by suitable valve manipulation. The oil remaining in chamber 6 is drained therefrom to a suitable sump (not shown) through a pipe 62, a valve 64, and a pipe 66. After the oil has been withdrawn from the chamber 6, the chamber is then filled by suitable valve manipulation with a straight-run naphtha contained within storage tank 68. The naphtha flows from the storage tank 68 to the chamber 6 through pipe 70, valve 72, pipe 74, valve 76, and the pipe 62. While being emptied of oil and filled with naphtha, the chamber 6 is vented through pipe 78, valve 80, pipe 82, and pipe 66. The naphtha serves to wash out any nonvolatile hydrocarbon residue that may be present on the desiccating agent within the chamber 6. The character of the naphtha is such that it contains substantially no nonvolatile constituents so that no residue is left deposited on the solid adsorbent during the subsequent heated gas treatment. In the event that it is desired continually to pass the straight-run washing naphtha through the chamber 6 for a period of time, then the naphtha passes from the upper portion of the chamber 25 through pipe 78, valve 80, and pipe 82, into the sump pipe 66. After the washing of the desiccating agent in the chamber 6 by the naphtha, the excess naphtha is then drained from the chamber 6 through the pipe 62, the valve 64, and the sump pipe 66.

After washing the desiccating agent in chamber 6 and draining of the wash naphtha through pipe 62, valve 64 and pipe 66, a stream of natural gas heated in the gas heater 12 is passed through pipe 34, valve 86 and the pipe 62 into the bottom of the chamber 6. The hot gas serves to vaporize the water adsorbed on the surface of the solid desiccating agent. The gas and water vapors pass from the chamber 6 through the pipe 78, 40 valve 88, and pipe 90 to the gas cooler 14 wherein the water condenses from the gas. The condensed water is removed from the gas in the water separator 16, and the gas is recycled through pipe 92, gas compressor 94, valve 96, and pipe 98 45 to the gas heater 12 and reused as described above. Pipes 100 and 102, controlled by suitable valves, may be employed for introducing and withdrawing gas from the system.

After the desired degree of revivification or 50 regeneration of the desiccating agent in chamber 6 has been effected, cool gas may be cycled through the chamber in order to cool the desiccating agent. This may be accomplished by cutting the steam supply off of the gas heater 12 and 55 cycling the gas as above described. After the desiccating agent in the chamber 6 has been cooled somewhat, a fresh charge of straight-run naphtha from the storage tank 68 is introduced into the chamber 6 in order further to cool the 60 desiccating agent therein. This charge of naphtha in chamber 6 covers or floods the solid desiccating agent and serves to prevent air from contacting the regenerated solid desiccating agent prior to the time that the chamber 6 is cut back into the desiccating system. It is desired not to 65 pass air over the desiccating bed because of its probable deleterious effects on the bed and oil retained therein; and it is desired also to keep all gas, including air, out of the transportation pipe line. Hence the gas remaining in chamber 6 after regeneration is completely displaced with naphtha. When the chamber 6 is to be cut back into the desiccating process, suitable valves are manipulated so that the charge of straight-run 70 naphtha contained therein flows directly into the 75

pipe line 10 with the oil that is passed through the system. This naphtha should have properties (particularly in respect to color and boiling point) which will permit of its being pumped directly into the pipe line with the hydrocarbon oil being treated without lowering the specifications of the latter below tolerance.

When the solid desiccating agent in chamber 2 or in chamber 4 needs revivifying or regenerating, these chambers may be cut out of the system by the manipulation of suitable valves and regenerated in the same manner as described in the foregoing in connection with chamber 6. When the chambers are connected in series in the manner described above, it is desirable that the first chamber into which the oil to be treated is flowed is the one which has the highest amount of adsorbed water therein so that the desiccating agent last contacted by the oil being treated is the agent which has been most recently revivified or regenerated.

While in the drawing three desiccating chambers have been shown and described, this number is of course not essential in accordance with the teachings of this present invention. For example, any number of chambers containing desiccating agents may be used and they may be connected in series or in parallel, or partly in series and partly in parallel, as desired.

While a particular embodiment of this invention is shown above, it will be understood, of course, that the invention is not to be limited thereto, since many modifications may be made, and it is contemplated, therefore, by the appended claims, to cover any such modifications as fall within the true spirit and scope of this invention.

I claim:

1. In the art of transporting a hydrocarbon liquid through a pipe line wherein said liquid is passed through a body of a solid desiccating agent for the removal of water dissolved in said liquid prior to the introduction of said liquid into said pipe line, the process of periodically regenerating said desiccating agent which comprises discontinuing the flow of hydrocarbon liquid through said body, washing said body of desiccating agent with a low-boiling hydrocarbon wash liquid, passing a stream of a substantially noncondensable and nonoxidizing inert gas through said body at an elevated temperature whereby to remove water therefrom in the form of a vapor, flooding said body with a low-boiling liquid hydrocarbon to displace all of said inert gas within said body to prevent the inclusion of gas within the hydrocarbon liquid when the desiccating agent is reused, and thereafter reestablishing the flow of said hydrocarbon liquid through said body of desiccating agent.

2. In the art of transporting a hydrocarbon liquid through a pipe line wherein said liquid is passed through a body of a solid desiccating agent for the removal of water dissolved in said liquid prior to the introduction of said liquid into

said pipe line, the process of periodically regenerating said desiccating agent which comprises discontinuing the flow of hydrocarbon liquid through said body, draining excess amounts of said liquid from said body, washing the drained body with a low boiling hydrocarbon wash liquid, draining excess wash liquid from said body, passing a stream of a substantially noncondensable and nonoxidizing inert gas through said body at an elevated temperature whereby to remove water therefrom in the form of a vapor, flooding said body with a low boiling hydrocarbon displacement liquid to displace all of said inert gas within said body to prevent the inclusion of gas within the hydrocarbon liquid when the desiccating agent is reused, and thereafter reestablishing the flow of said hydrocarbon liquid through said body of desiccating agent whereby said displacement liquid and said hydrocarbon liquid pass together into said pipe line.

3. In the art of transporting a hydrocarbon liquid through a pipe line wherein said liquid is passed through a body of a solid desiccating agent for the removal of water dissolved in said liquid prior to the introduction of said liquid into said pipe line, the process of periodically regenerating said desiccating agent which comprises discontinuing the flow of hydrocarbon liquid through said body, draining excess amounts of said liquid from said body, washing the drained body with a low boiling hydrocarbon wash liquid, draining excess wash liquid from said body, passing a stream of a substantially noncondensable and nonoxidizing inert gas through said body at an elevated temperature whereby to remove water therefrom in the form of a vapor, thereafter passing a cooler stream of said gas through said body to lower the temperature, then flooding said body with a low boiling hydrocarbon displacement liquid to displace all of said inert gas within said body to prevent the inclusion of gas within the hydrocarbon liquid when the desiccating agent is reused, and thereafter reestablishing the flow of said hydrocarbon liquid through said body of desiccating agent whereby said displacement liquid and said hydrocarbon liquid pass together into said pipe line.

4. The process recited in claim 3 wherein said gas is natural gas.
